UNITED STATES PATENT OFFICE.

ALFRED F. WINSLOW, OF KANSAS CITY, MISSOURI.

DESIGN FOR A DISCOUNT-CHECK.

48,740.

Specification for Design.

Patented Mar. 14, 1916.

Application filed January 31, 1916. Serial No. 75,445. Term of patent 3½ years.

To all whom it may concern:

Be it known that I, ALFRED F. WINSLOW, a citizen of the United States, residing at Kansas City, in the county of Jackson and State of Missouri, have invented a new, original, and ornamental Design for Discount-Checks, of which the following is a specification, reference being had to the accompanying drawing, forming a part thereof.

In the drawing—Figures 1 and 2 are plan views of the opposite faces, respectively, of a discount check, showing my new design.

I claim:

The ornamental design for a discount check, as shown.

A. F. WINSLOW.
